[57] CLAIM

The ornamental design for a cabinet housing for optical imaging of fingerprints, as shown herein.

DESCRIPTION

FIG. 1 is a top, front, and right side perspective view of a cabinet housing for optical imaging of fingerprints showing our new design;

FIG. 2 is a front elevational view thereof;

FIG. 3 is a rear elevational view thereof;

FIG. 4 is a right side elevational view thereof;

FIG. 5 is a left side elevational view thereof; and,

FIG. 6 is a top plan view thereof.

FIG. 1

FIG. 2FIG. 3

FIG. 4

FIG. 5**FIG. 6**
